METAL COUNTER TOP CONSTRUCTION

Glenn H. Norquist, Jamestown, N. Y.

Application February 10, 1947, Serial No. 727,582

9 Claims. (Cl. 311—106)

1

This invention relates to an improved counter top construction, and more particularly to a metal clad counter top having a raised rim formation extending around the table section thereof and presenting unbroken metal facing surfaces formed of sheet metal supported and reinforced by backing sections of fibrous material.

Metal clad counter tops constructed in accordance with this invention may be formed from a single sheet of light gauge metal stiffened and supported by fibrous backing sections. This improved counter top is characterized by a raised rim formation extending along one or more edges of the table section thereof. The metal facing sheet is formed so as to cover all exposed faces of the counter top free from visible seams, all metal facing surfaces being backed up and supported by fibrous backing selections so that the metal facing surfaces cannot readily be dented or deformed. The metal facing sheet selected is preferably a bright metal, such as stainless steel, Monel metal, aluminum, brass or copper, which may be polished and finished on the top side prior to cutting, shaping and bending thereof.

After the metal facing sheet has been polished, the corners thereof are cut to the proper shape, and a fibrous backing panel then adhesively bonded to the rear, unfinished side of the metal facing sheet. The fibrous backing panel may be formed from laminated plywood, hard pressed fiberboard, composition board or like fibrous sheetings commonly used in the building industry. The fibrous backing panel comprises a table backing section shaped to be adhesively bonded to the table section of the metal sheet, front and rear apron backing sections designed to be adhesively bonded to the front and rear apron sections of the metal sheet, and side apron backing sections designed to be adhesively bonded to side apron sections of the metal sheet.

The apron backing sections, as bonded to the metal facing sheet, are spaced from the adjacent edges of the table backing section by an open groove of predetermined width. The ends of the apron backing sections are cut on a bevel so that the end faces thereof are sloped at an angle of 45° with respect to its metal attaching face. The elongated edge of each of the apron backing sections, next adjacent the table backing section, is also beveled or sloped with respect to the metal attaching face thereof. The backing panel as bonded to the metal facing sheet, thus presents the apron sections thereof in spaced relation with respect to the table backing section in a manner to permit the formation of the raised

2

rim which is to extend around the edges of the table section of the metal sheet when the counter top construction has been formed.

The metal clad panel is placed in a die press and the peripheral edge portions of the table section of the metal sheet, unsupported by fibrous backing, are formed into a raised rim extending around all of the edges, or a selected number of the edges, of the table section of the metal facing sheet. The open grooves or channels defined between the adjacent edges of the table backing section and the apron backing sections are so spaced and arranged as to permit shaping of the metal clad panel to provide depending apron sections. A bonding adhesive may be applied to the open channels prior to bending formation of the metal clad panel.

The metal clad panel may be shaped into counter top form in a clamping frame which serves to bend the apron sections into position substantially at right angles to the table section. In this forming operation, the longitudinally extending beveled edges of the apron sections will fold over into the open grooves and will be brought into abutment against the rear face of the adjacent raised rim formations of the metal sheet to provide a firm backing support therefor. While the apron sections are still retained in fixed position by the clamping frame, the flange sections of the metal facing sheet are turned inwardly and stiffening strips inserted to fit snugly within the pocket form by the inturned flange sections and the adjacent formed apron sections. The stiffening strips thus provide a rectangular frame which further strengthens the construction. The inturned flange sections may be secured to the stiffening frame as by nails or screws, whereupon the partially assembled counter top may be removed from the clamping frame and the bonding adhesive previously deposited in the open channel grooves permitted to harden and set. Fibrous filler boards may be employed to fill the space within the stiffening frame to further stiffen and strengthen the construction.

The metal facing sheet is provided with lip portions extending from the ends of the apron sections thereof which are folded over the adjacent inclined ends of the apron backing sections before the apron sections are shaped into formed position. When the apron sections have been shaped to extend substantially at right angles to the table section of the metal clad panel, the adjacent lip portions of the metal sheet will be in face-to-face contact and extend diagonally in

wardly from each vertical corner of the formed counter top. A seam of soldering or welding metal is applied to the exterior surface of the joint defined between the adjacent lip portions, the molten metal seeping inwardly between the adjacent faces of the lip portions to firmly bond the adjacent lip portions into integral union. The exterior surface of the metallic seam may be burnished or polished to give the corner a rounded and finished appearance.

Counter tops as thus constructed present a metal faced table section having a raised rim formation which may extend around all the edges or any selected number of the edges of the table section. The rim formation enhances the appearance of the construction, and serves to prevent liquids or solids on the table section from overflowing to the floor. The metal faced apron sections present smooth and rounded corners free of crevices or visible joints. The inwardly extending metal flange sections present a mitered joint between the adjacent ends thereof, which joint can also be covered by a seam of soldering or welding metal. The inturned flange sections present a finished appearance and are designed to extend inwardly a sufficient distance so as to be at least partially concealed by the structure upon which the counter top is to be supported.

The fibrous backing sections bonded to the rear face of the metal facing sheet prevent wrinkling, warping or other undesired distortions of the metal sheet during shaping and bending thereof into counter top form, and in addition insures stiffness, strength and rigidity to the construction, provides a sound deadening effect so that the metal facing surfaces will not reverberate or produce a metallic ring when drummed upon, and in addition permits the use of a relatively light gauge metal facing sheet which can be worked and shaped with relative ease. The framing strips snugly fitted within the U-shaped cavity defined by the apron sections and the adjacent inturned flange sections, and the filler boards fitted within the confines of the stiffening frame, further enhances the rigidity and strength of the construction without substantially increasing its weight. The counter top construction has all the exposed surfaces thereof covered by an unbroken metallic layer which may be made from bright metal and thus can be easily cleaned and kept in a highly sanitary condition.

An object of this invention is to provide an improved counter top construction which can be manufactured at a relatively low cost, which presents a table section bordered by a raised rim formation and depending apron sections whose exposed surfaces are covered by a continuous and unbroken metal facing free of visible joints; providing a counter top which is durable, strong and lasting in use and yet relatively light in weight, and which is attractive and pleasing in appearance.

Other objects and advantages of this invention will become apparent as the disclosure proceeds.

Although the characteristic features of the invention will be particularly pointed out in the claims appended hereto, the invention itself, and the manner in which it may be carried out, may be better understood by referring to the following description taken in connection with the accompanying drawings forming a part hereof, in which

counter top, this view also showing elemental details of the clamping and holding frame as the same would appear when viewed along line 19-19 of Fig. 17; and

Fig. 19A is an enlarged fragmentary longitudinal cross-sectional view of the partially assembled modified counter top construction, this view additionally showing elemental details of the clamping and holding frame therefor as the same would appear when viewed along line 19-19 of Fig. 17.

Similar reference characters refer to similar parts throughout the several views of the drawings and specification.

The improved counter top construction, as generally illustrated in Fig. 1 to Fig. 4A inclusive, comprises a metal clad table section *a* having front and rear apron sections *b*, and side apron sections *c*. The lower edge of the front and rear apron sections *b* are each provided with an inturned flange section *d*, and the side apron sections *c* are each provided with an inturned flange section *e*. The ends of the side apron sections *c* and the adjacent ends of the front and rear apron sections *b* meet to form the vertical front and rear corners of the counter top construction. The adjacent ends of the inturned flange sections *d* and *e* meet to form a diagonal joint as shown more particularly in Fig. 2. The table section *a* and the surrounding apron sections *b* and *c* are reinforced and held in rigid position by a rectangular shaped stiffening frame *f* which seats under the inturned flange sections *d* and *e* of the construction, as shown more particularly in Figs. 2 to 4A inclusive. The space defined within the stiffening frame *f* may be filled with fibrous filler *g* which provides further reinforcement to the construction.

An important feature of this invention is the provision of a rim formation *h* which defines the peripheral contour of the table section *a*. In the counter top construction shown in Fig. 1, the rim formation *h* extends along the front, rear and side boundaries of the table section *a* so as to completely surround and enclose the table section. In the modified counter top construction shown in Fig. 1A, the rim formation *h* is shown as extending along only the front and side boundaries of the table section *a*. The rim formation *h* serves to prevent spillage of materials from the table section *a* to the floor.

This improved counter top may be made in any desired dimension to provide a top construction for restaurant, bar and merchandise counters, for cabinets, tables and other supporting structures as may be desired. For purposes of illustration, the improved counter top is shown in Fig. 1 and Fig. 1A as mounted upon a cabinet structure *S*. This counter top may be easily secured to either wood or metal supporting structures *S* by the application of screws or brackets and concealed from view. The table section, the apron sections, the inturned flange sections and the rim formations present metal facing surfaces free from crevices and visible joints.

The exposed facing surfaces of this improved counter top construction can be economically manufactured from a single substantially rectangular sheet of bright metal such as stainless steel, aluminum alloy, Monel metal, magnesium alloy, tin, brass or copper, or ordinary sheet steel which is later to receive an enamel finishing coat. The metal facing sheet *w* is initially substantially rectangular in form, as indicated in dotted lines in Fig. 5, and may be relatively thin metal, of

from 18 to 30 gauge in thickness. As an initial step in the manufacture, the rectangular metal facing sheet *w* is first run through a sander or polisher to give one side of the sheet its final and ultimate polish and finish.

The corners *w'* of the rectangular metal sheet are then trimmed off as shown in Fig. 5, which operation can be quickly performed on a metal shearing press. As thus formed, the metal facing sheet presents a table section 1, front and rear apron sections 2 defined by the generally parallel extending bending lines 3, and side apron sections 4 defined by the generally parallel extending bending lines 5. The front and rear apron sections 2 are each provided with a flange section 6 defined by a bending line 7, and the side apron sections 4 are each provided with a flange section 8 defined by a bending line 9.

A lip portion 10 extends from each end of the front and rear apron sections 2 and is defined by a bending line 5' substantially in alignment with the adjacent bending line 5. Each end of each of the side apron sections 4 is also provided with a lip portion 11 defined by a bending line 3' substantially in alignment with the adjacent bending line 3. The adjacent lip portions 10 and 11 are separated by a diagonally extending cut 12 which terminates at the adjacent corner of the table forming section 1. Each end edge 6' of the front and rear flange sections 6 extends from the adjacent corner of the adjacent apron section 2 at an angle of approximately 45° with respect to the adjacent bending line 7. Each end edge 8' of each of the side flange sections 8 extends from the adjacent corner of the adjacent side apron section 4 at an angle of approximately 45° with respect to the adjacent bending line 9.

It will be appreciated that the bending lines 3 and 7, 5 and 9, 5' and 3' are the lines along which the metal facing sheet, as shown in Fig. 5, will be bent in a later forming operation. These bending operations are performed only after the fibrous backing panel *p* has been bonded to the rear surface of the metal facing sheet *w*.

The fibrous backing panel *p* as shown in Figs. 6 to 9A inclusive, may be formed of laminated plywood, hard pressed fiberboard, pressed composition board, or like relatively strong fibrous sheeting commonly used in the building industry. The fibrous backing panel *p* is preferably approximately $\frac{1}{4}$ inch in thickness, although it will be appreciated that the fibrous backing panel may vary in thickness from as low as $\frac{1}{8}$ of an inch to $\frac{1}{2}$ inch or more in thickness.

The backing panel shown in Fig. 6 comprises a table backing section 21 of generally rectangular form with square cut edges of a size to accurately cover the table in section 1 of the metal sheet within the raised rim formations *h* thereof. Separately formed front and rear apron backing sections 22 are provided of a size to accurately cover the inside face of the front and rear apron sections 2 of the metal facing sheet. Each end 23 of each of the apron backing sections 22 is sliced on an incline so as to present an end face which extends at an angle of approximately 45° to the metal attaching face of the apron backing section. That longitudinal edge 26 of each of the apron backing sections 22 which is to be positioned next adjacent the table backing section 21, is also cut to provide a slanting face edge 26 which partially extends at an angle of approximately 45° to the metal attaching face of the backing section.

Separately formed side apron backing sections 75

24 are provided of a size and shape to accurately cover the inside face of the side apron sections 4 of the metal facing sheet. Each of the side apron backing sections 24 have the ends thereof cut on a slant so as to present end facing edges 29 inclined at an angle of 45° with respect to the metal attaching face of the apron section. Each apron backing section 24 has one longitudinal edge thereof cut on a miter so as to present an inclined edge face 27 which may be slightly rounded and partially inclined at an angle of approximately 45° to the metal attaching face of the apron section.

It will be noted, as shown in Figs. 6, 7 and 8, that the table backing section 21 and the apron backing sections 22 and 24 may be separately cut and formed with a minimum waste of material. These sections are then connected together to provide a backing panel unit which will hang together when adhesively applied to the metal facing sheet *w*. These backing sections may be conveniently connected together when laid flat upon a work bench provided with suitable corner guide blocks 47 which permit convenient interfitting of the sections as shown in Fig. 6. The longitudinally extending inclined edge 26 of the front and rear apron backing sections 22 are each spaced from the adjacent edge of the table backing section 21 a specified distance to provide an open groove 23 therebetween. The width of the open groove 23 may be accurately defined by removable wedge blocks 49 inserted therein. The width of each open groove 23 is such as to snugly receive the adjacent edge 26 of the apron section when the metal clad panel is shaped into counter top form as hereinafter described. The inclined longitudinal edge 27 of each of the side apron backing sections 24 are also accurately spaced, as by the use of wedge blocks 49, from the adjacent edge of the table backing section 21 so as to provide an open groove 25 designed to snugly receive the adjacent edge 21 of the apron section when the counter top has been formed.

The front and rear apron backing sections 22 and the side apron backing sections 24, thus accurately spaced by the defined open grooves 23 and 25 from the adjacent edges of the table backing section 21, are temporarily connected to the table backing section 21 by driving suitable fasteners, such as a corrugated staple fastener 48 as shown in Figs. 6 and 9, into the adjacent edge portions of the sections. The spacing assembly of the table backing section 21 and the apron backing sections 22 and 24 may be quickly performed by the use of a simple jig arrangement, as illustrated in Fig. 6 in its elemental form. These sections can then be quickly connected together in their proper spaced relationship by driving a few removable fastener elements 48 into the adjacent edge portions thereof. The assembled backing panel as shown in Fig. 6 is now ready to be adhesively secured to the rear face of the metal facing sheet, as illustrated in Fig. 10. The lip portions 10 and 11 of the metal facing sheet may be bent upwardly to abut the adjacent end faces of the backing panel, thereby to insure accurate registry of the backing panel with the metal facing sheet until the adhesive bond therebetween has firmly set.

The fibrous backing panel *p* may also be formed from a one-piece substantially rectangular sheet of fibrous backing material to provide a panel as illustrated in Figs. 6A, 7, 8A, and 9A, ready for attachment to the metal facing sheet. In

making the shaped panel here shown, a rectangular backing sheet is provided, cut to the desired size to define the exterior longitudinal edges of the apron sections 22 and 24. The corners of the rectangular panel are then cut away on a corner notching machine, whose cutting knives are so arranged as to cut each end 28 of the apron backing section 22 and the adjacent end 29 of the adjacent apron backing section 24 on an incline so that the end face 28 and the end face 29 will extend at an angle of approximately 45° to the metal attaching face of these apron sections.

After the backing panel shown in Fig. 6A has been corner notched as above indicated, the same is run through a grooving machine which operates to cut the open grooves 25 therein. The grooving wheels of this machine will also cut the adjacent side edges of the side apron sections 24 so that they will present inclined faces 27. This grooving machine is so adjusted that it will leave uncut necks 31 along each groove 25. A second grooving machine is employed, having one grooving wheel set to cut the open groove 23 which defines the front apron section 22 from the table backing section 21. This grooving wheel operates to leave uncut necks 31 along the open groove 23, so that the open groove is only shallow cut as at 23' over the limited length necks 31 as shown in Fig. 9A.

If a counter top as shown in Fig. 1 is to be constructed, an open groove 23 with spaced necks 31 will also be cut in the backing panel to define the rear apron section 22 from the adjacent rear edge of the table backing section 21. To illustrate the flexibility of these operations, Figs. 6A and 8A show a continuous V-shaped groove 30 cut into the backing panel to define the rear apron section 22 from the adjacent rear edge of the table backing section 21. A V groove 30 such as here shown would be applied to the backing panel in event a counter top construction is to be formed which has no rim formation along the rear edge of the table section as illustrated in Fig. 1A. The fibrous backing panel p, corner notched and grooved in the manner illustrated in Figs. 6A, 7, 8, 8A and 9A, will hang together as an integral unit, ready to be adhesively bonded to the metal facing sheet.

The backing panel having the backing sections thereof connected by the staple fasteners 48, as shown in Fig. 6, is coated with a bonding adhesive on the metal attaching face thereof and the panel applied to the rear face of the prepared metal facing sheet as shown in Fig. 5. To facilitate proper registry of the backing panel, it is preferably desirable to upturn the lip portions 10 and 11 of the metal facing sheet along the bend lines 5' and 3' thereof. The lip portions 10 are then driven down to snugly overlie the adjacent inclined end faces 28 of the front and rear backing sections 1 and 2, and the lip portions 11 are driven down to snugly overlie the inclined end faces 29 of the side apron backing sections 24. The metal clad panels thus assembled as shown in Fig. 10 may be stacked together under pressure until the bonding adhesive has become fully set so as to tenaciously bond the backing sections to the metal facing sheet. The staple fasteners 48 can then be withdrawn from the backing panel, at which stage of the production the metal clad panel appears as shown in Fig. 10, ready for shaping into counter top form.

In event a backing panel constructed in the form as illustrated in Fig. 6A is employed, this

backing panel is adhesively bonded to the metal facing sheet and the upwardly extending lip portions 10 and 11 of the metal sheet driven down to snugly overlie the adjacent inclined end faces 28 and 29 respectively of the adjacent apron backing sections. The metal clad panels as thus formed may be stacked under pressure until the bonding adhesive has become thoroughly dry. The metal clad panel is then again run through the grooving machines merely to remove the spaced connecting necks 31 which connect the apron backing sections to the table backing sections. It will here be particularly noted that the backing panel has been so formed prior to its application to the metal facing sheet, that the connecting necks 31 each present an under surface 32 which is spaced from the metal attaching face of the panel as shown in Fig. 9A. It will thus be noted that the connecting necks 31 do not become adhesively bonded to the metal facing sheet, and consequently the neck portions 31 can be easily and cleanly removed to leave clean continuous grooves 23 and 25 free from interfering backing material particles. As thus constructed, the metal clad panel formed from the backing panel shown in Fig. 6A and bonded to the metal facing sheet shown in Fig. 5 will be ready for assembly operations.

Assuming a counter top is to be constructed having a raised rim formation h which is to extend completely around the table section a as shown in Fig. 1, the metal clad panel as shown in Fig. 10 is placed in a die press which operates to deform the peripheral portions 13, 14 and 15 of the table section of the metal facing sheet as shown in Figs. 11, 12 and 13. In event a counter top is to be made without a raised rim formation along the rear edge thereof as shown in Fig. 1A, only the front and side peripheral portions 13 and 14 of the table section 21 of the metal sheet is deformed as illustrated in Figs. 11A, 12 and 13A.

The rim forming operation may be performed in one or more stages as desired by the use of one or more die presses illustrated in elemental form in Figs. 12, 13 and 13A. The die press elements shown in Figs. 12 and 13 are designed to form the rim formations 13, 14 and 15 in the metal clad panel as shown in Fig. 11. The die press is provided with a press table 50 having a flat table surface 51 upon which the table backing section 21 is supported, and raised table surfaces 52 upon which the apron backing sections 24 are supported. The press is equipped with vertically reciprocable press blocks 53, each having a die face 54 designed to exert downward pressure as at 55 against the metal sheet directly over the open grooves 25 so as to bend and shape the peripheral side edge portions 14 of the metal table section 1 to the desired rim conformity. In the second die press operation, the table backing section 21 is supported upon the table surface 51 of the press table 50 and the apron backing sections 22 are supported upon the raised surfaces 56 thereof. A pair of reciprocating die blocks 57, each having a die face 58, operate to exert downward pressure as at 55 the front and rear marginal portions of the metal table section to form the rim facings 13 and 15 of the desired contour. The die blocks 53 and 57 are so formed as to merge the adjacent ends of the rim faces 14, 13 and 15 into a smooth and unbroken raised corner bead 13'. If necessary, corner die blocks may be employed to insure the desired rounded and con-

tinuous contour at the corners of the rim formation *h*.

In the rimming formation of the metal clad panel as shown in Fig. 11A, employed in forming the counter top construction shown in Fig. 1A, the side rim formations *14* may be formed on the die press as illustrated in Fig. 12 and above described. Since only the front edge of the table section *21* is to receive the rim formation, a die press as shown in Fig. 13A may be employed to 10 shape the front rim formation. The table backing section *21* of the metal clad panel is supported on the table surface *51* of the press table *50* and the front apron backing section *22* is supported upon the raised table surface *56* thereof. The die 15 block *57* having the die face *58* operates to shape the front edge portion of the metal table section *1* to provide the inclined rim face *13*. A die block *59* having a flat die face *59'* may be provided to exert pressure against the table section *1* and 20 rear apron section *2* of the metal sheet to hold the metal clad panel in proper position.

When the rim facing portions *13*, *14* and *15* have been formed at the peripheral boundary of the table section *1* of the metal facing sheet as 25 illustrated in Figs. 11, 12 and 13, the metal clad panel is in condition for shaping into counter top form as illustrated in Figs. 14, 15 and 16. Immediately before the shaping operation, a strip of bonding adhesive may be placed within the 30 grooves *23* and *25*. Thereupon the front and rear apron sections *d* and the side apron sections *c* are bent to extend substantially at right angles to the table section *a* to provide the partially 35 formed counter top as illustrated in Figs. 14, 15 and 16. The front and rear flange sections *d* and the side flange sections *e* are also bent inwardly so as to extend substantially at right angles to their associated apron sections *b* and *c*. This 40 operation can be performed by hand or by a simple shaping jig or fixture.

As thus formed, each open groove *23* will receive the adjacent edge portion *26* of the apron backing section *22* with the inclined edge *26* snugly seating against the under-face of the 45 raised metal rim *13* and *15*, as shown in Fig. 16. The open grooves *25* will likewise receive the adjacent edge portion *27* of the apron backing sections *24* with the inclined edge *27* firmly abutting against the rear face of the raised metal rim 50 formations *14* as shown in Fig. 15. Upon completion of the shaping operation, the adjacent metal lip portions *10* and *11* are in face-to-face contact, as shown more particularly in Fig. 2a. The metal flange section *6* may be bent inwardly along the bending line *7* to provide a slightly 55 rounded corner *7'* as shown in Fig. 16, and the metal flange sections *8* may be bent inwardly along their bending lines *9* to provide slightly rounded corners *9'* as shown in Fig. 15.

The counter top construction shown in Fig. 1A may be similarly formed as shown in Figs. 14A, 15 and 16A. As the first step, a bonding adhesive is deposited in the open grooves *23* and *25* and in the V groove *30* of the metal clad panel 60 as shown in Figs. 11A, 12 and 13A, and the front and rear apron sections *b* and the side apron sections *c* then bent to extend substantially at right angles to the table section *a*. As thus formed the inclined edge *26* of the front apron backing section *22* will snugly seat against and support the overlying metal rim formation *13*, and the inclined edges *27* the side apron backing sections *24* will seat against and provide a support for the underlying metal rim formations *14*. The V 75 strips *37* extend between the adjacent ends of

groove *30* will close to form a mitered joint *30'* as shown in Fig. 16A, providing a counter top construction which has no raised rim adjacent the mitered joint *30*.

It will be appreciated that the construction shown in Fig. 14A, the end portions *14'* of the side rim formations *14* are shaped in the die press to taper off in a slightly rounded contour as shown in Fig. 16A. It will also be noted that the rear metal apron section *2* at the flat edge of the table section *a* would preferably be made of slightly less height than the apron sections which are crowned by a rim formation, as is readily apparent by referring to Fig. 16A. In the modified construction shown in Fig. 1A, the adjacent metal lip portions *10* and *11* will also be brought into face-to-face contact, as shown more particularly in Fig. 2a, upon completion of the shaping operation.

The front and rear apron sections *b* and the side apron sections *c* may be held in their proper formed position by a clamping frame as illustrated in Figs. 17 to 19A inclusive. The clamping frame may be associated with a suitable work table *60* upon which the partially formed counter top construction is supported, the table having associated therewith a fixed clamping bar *61* which may be fixed to the work table and an adjustable clamping bar *62* between which the front and rear apron sections *b* are clamped. Adjustment of the front clamping bar *62* may be effected by the use of adjusting bolts *63* which are threaded into a fixed bar *64*. By manipulating the head portions *65* of the bolts *63*, the clamp bar *62*, engaged by the ends of the adjusting bolts *63*, may be readily manipulated. The side apron sections *c* may likewise be clamped between a fixed clamping bar *66* and an adjustable clamping bar *67*, the adjustable clamping bar *67* being manipulated by means of threaded bolts *68* extending through threaded apertures associated with the fixed bar *69*, the bolts *68* having suitable manipulating heads *70*. The supporting table *60* upon which the metal clad panel is supported may be provided with suitable formed grooves *71* as required to receive the adjacent rim formation *h* of the panel. By the use of a clamping frame as above generally described, the front and rear apron sections *b* and the side apron sections *c* may be held in their intended fixed position substantially at right angles to the table section *a*.

A reinforcing and stiffening frame *f* is then inserted under the inturned metal flange sections *d* and *e* as shown in Figs. 17 to 19A inclusive. This is preferably accomplished by providing a pair of front and rear stiffening strips *36* which may be made of wood or like fibrous material, each shaped to snugly fit within the U-shaped pocket defined by the adjacent apron section *b* and the flange section *d*. Each of the stiffening strips *36* preferably extend along the full side face of the adjacent apron backing section *22*. The stiffening strips *36* may be coated with a bonding adhesive which upon hardening will adhesively secure the stiffening strip to the adjacent faces of the metal flange section *6*, apron backing section *22* and table backing section *21*. A pair of side edging strips *37*, suitably shaped and coated with adhesive, are inserted within the pocket defined by the side flange sections *e* and side apron sections *c* as shown more particularly in Figs. 19 and 19A. The side stiffening strips *37* extend between the adjacent ends of

13

the front and rear stiffening strips 36 so the adjacent ends of the stiffening strips may have a notched interlock and may be firmly secured together by screws or nails 39 to provide a relatively rigid reinforcing frame *f*.

Reciprocal pressure blocks 72 may be provided to exert pressure against the inturned flange section *d* and *e* of the apron sections to force the rim formation *h* within the table groove 71, and thus assure a firm adhesive bond between the inclined edges 26 and 27 of the apron backing sections and the adjacent rear face of the metal rim formations 13, 14 and 15. Where the counter edge is not provided with a raised rim formation, no table groove need be provided as shown in Fig. 19A, the adjacent pressure block 72' serving only to effect a firm adhesive bond at the mitered joint 30'.

Before the partially assembled counter top is removed from the clamping frame as shown in Figs. 17 to 19A inclusive, it is desired to secure the inturned flange sections *d* and *e* and to the adjacent framing strips 36 and 37 as by screws or nails 39, which thus serve to hold the flange sections *d* and *e* and the apron sections *b* and *c* in proper assembled relationship until the bonding adhesive *x* has fully set. If no bonding adhesive *x* is used, a sufficient number of space screws or nails 39 are employed to maintain the construction in assembled position after removal thereof in the clamping frame.

To further stiffen and strengthen the construction, the space defined within the stiffening frame *f* may be filled with a backing filler *g* as shown more particularly in Figs. 2 to 4A inclusive. The backing filler *g* may comprise a plurality of boards 40 formed of wood or other fibrous material which may extend either longitudinally or transversely of the counter top construction. The filler boards 40 may have a notched interlocked connection 38 with the stiffening strips 36 and 37 as shown more particularly in Figs. 3, 4 and 4A, and spaced to permit expansion.

Since all the exposed faces of the metal surfacing sheet have been polished while the sheet was in flat form as shown in Fig. 5, the only remaining operation to give the counter top construction its final finished appearance is to apply a seam 45 of soldering or welding metal to the vertical corners as shown in Figs. 1, 1A and 2a. The molten solder or welding metal will seep in between the adjacent faces of the inturned lip portions 10 and 11 of the metal sheet so as to integrally bond the lip portions 10 and 11 together over a substantial surface area, providing a corner construction of great strength. The exterior surface of the metal seam 45 may be burnished and polished to provide a smooth and rounded corner, free of cracks or visible lines of juncture. A seam of soldering or welding metal may also be applied to the adjacent edges 6' and 8' of the flange sections 6 and 8 as shown in Fig. 2 and Fig. 2b to provide a smooth joint therebetween. The exposed surface of the metal seam may be polished or burnished to provide a smooth joint free of cracks or any visible line of juncture.

Counter tops may be made according to this invention in any desired width or length to satisfy any requirements. The apron sections *b* and *c* may also be made of any desired height and the inturned flange sections *d* and *e* may extend inwardly to any desired distance. The raised rim *h* may extend along only one edge of the table section, or may be formed to extend along two or

14

three edges, or along all the edges of the table top section as may be desired. Thus this improved counter top construction may be provided with any desired number of raised edging rims and may be made in any desired size to satisfy any dimensional requirements.

By reason of the fibrous backing sections which cover the entire area of the metal table section 1, the front and rear metal apron sections 2, the metal side apron sections 4 and the raised rim formations 13, 14 and 15, an improved counter top construction is provided which is free from metallic sound or ring when drummed upon. The application of fibrous backing sections to the sheet metal prior to bending formation thereof, permits the use of a relatively light gauge metal facing sheet, which is prevented from wrinkling or warping during and after manufacture. By constructing the counter top in the manner above described, the exposed faces of the metal sheet may be sanded and finished rapidly and economically in its flat condition and before any forming operations are executed thereon, thus avoiding the more difficult and time consuming finished operations normally necessary after the counter top has been constructed. By forming the facing surfaces of the counter top from a single piece of sheet metal, crevices and cracks in which foreign matter may gather is substantially avoided. Extensive and time consuming welding and soldering operations, heretofore necessary in the manufacture of metal clad counter tops as heretofore constructed, are also avoided.

Metal clad counter tops constructed as above described are unusually light in weight, since strength is achieved by the use of relatively light fibrous backing sections and wood or fibrous filler boards or strips. The counter top nevertheless possesses unusual strength and rigidity and will not warp or deform. Since all exposed surface areas of the metal sheet, including the raised rim formation, are backed up by fibrous backing sections, the finished metal surface cannot readily be dented, even though formed of a relatively light gauge metal sheet. Counter tops may be manufactured in accordance with this invention to snugly fit and seat upon any desired supporting structure *S*. The inturned flange sections *d* and *e* may be made of sufficient width so that the inner ends thereof and the associated securing screws or nails 39 are concealed by the structure upon which the counter top is supported.

Counter tops having rim formations may be manufactured in accordance with the teachings of this invention on a mass production basis at greatly reduced cost as compared with methods heretofore employed in the construction of metal clad counter tops. These improved counter tops are lasting in use, provide a construction of lasting utility, and are highly attractive and appealing in appearance and finish.

While certain novel features of the invention have been disclosed herein, and are pointed out in the annexed claims, it will be understood that various omissions, substitutions, and changes may be made by those skilled in the art without departing from the spirit of the invention.

What is claimed is:

1. An improved counter top construction having a table top section, a raised rim formation extending along the edges of said table section, and a plurality of apron sections depending from said rim formation, said counter top being formed from a one piece metal sheet shaped to form

15

the facing surfaces for said table section, rim formation and apron sections, and fibrous backing sections bonded to said metal facing sheet to provide backing support for the table section, rim formation and apron sections of said metal facing sheet, the adjacent ends of said apron backing sections being mitre cut to provide spaced substantially parallel end faces presenting an open joint therebetween, said apron sections of the metal sheet having a lip portion at the adjacent ends thereof extending inwardly and in hugging contact with the adjacent mitre cut end of the adjacent apron backing section, the adjacent metal lip portions being in face-to-face contact.

2. An improved counter top construction having a table top section, raised rim formations extending along a plurality of peripheral edges of said table section, and apron sections depending from said raised rim formations, said counter top being formed from a metal sheet shaped to form the facing surfaces for said table section, raised rim formations and apron sections, fibrous backing sections bonded to said metal facing sheet to provide backing support for the table section, rim formations and apron sections of said metal facing sheet, the adjacent ends of said apron backing sections being mitre cut to provide spaced substantially parallel end faces presenting an open joint therebetween, said apron sections of the metal sheet having a lip portion at the adjacent ends thereof extending inwardly and in hugging contact with the adjacent mitre cut end of the adjacent apron backing section, the adjacent metal lip portions being in face-to-face contact, the space defined within said apron sections being filled with fibrous filler providing a light-weight counter top presenting finished metal facing surfaces supported and reinforced by fibrous material.

3. An improved counter top construction having a table top section, raised rim formations extending along the peripheral edges of said table section, apron sections depending from said raised rim formations, and flange sections extending inwardly from said apron sections, said counter top being formed from a metal sheet forming the facing surfaces for said table section, rim formations, apron sections and flange sections, and fibrous backing sections bonded to said metal facing sheet to provide backing support for the table section, rim formations and apron sections of said metal facing sheet, the adjacent ends of said apron backing sections being mitre cut to provide spaced substantially parallel end faces presenting an open mitred joint therebetween, said apron sections of the metal sheet having a lip portion at the adjacent ends thereof extending inwardly and in hugging contact with the adjacent mitred end of the adjacent apron backing section, the adjacent metal lip portions being in face-to-face contact.

4. An improved counter top construction having a table top section, raised rim formations extending along adjacent edges of said table section, and apron sections depending from said rim formations, said counter top being formed from a one piece metal sheet forming the facing surfaces for said table top section, rim formations and apron sections, a fibrous backing section bonded to said metal facing sheet providing backing support for the table section of said metal facing sheet, fibrous backing sections bonded to said metal facing sheet each providing back-

16

ing support for the adjacent apron section of said metal sheet, an edge of each apron backing section being shaped to substantially conform to the inner surface contour of the adjacent rim formation of said metal sheet and in substantial abutment there-against to provide backing support therefor, said apron sections of the metal sheet having the lip portions at the adjacent ends thereof extending inwardly and in hugging contact with the adjacent mitred ends of the apron backing sections with the adjacent metal lip portions in face-to-face contact, and a seam of bonding metal covering the exterior joints between said inturned lip portions bonding said lip portions into integral union.

5. An improved counter top construction having a table top section, raised rim formations extending along the peripheral edges of said table section, and apron sections depending from said rim formations, said counter top being formed from a one piece metal sheet forming the facing surfaces for said table top section, rim formations and apron sections, a fibrous table backing section bonded to said metal facing sheet providing, backing support for the table section, fibrous apron backing sections bonded to said metal sheet each providing a backing support for the adjacent apron section of said metal sheet, the upper edge of each of said apron backing sections being shaped to substantially conform to the inner surface contour of the adjacent rim formation of said metal sheet and in substantial abutment thereagainst to provide a backing support therefor, the adjacent ends of said apron backing sections presenting mitred joints therebetween, said apron sections of the metal sheet having a lip portion at the adjacent ends thereof extending inwardly and in hugging contact with the adjacent mitred end of the adjacent apron backing section, the adjacent metal lip portions being in face-to-face contact, and a seam of bonding metal covering the exterior joint between said inturned lip portions bonding said lip portions into integral union, the space defined within said apron sections being filled with fibrous filler providing a light weight counter top presenting finished metal facing surfaces supported and reinforced by fibrous material.

6. An improved counter top construction having a table top section, raised rim formations extending along the peripheral edges of said table section, apron sections depending from said rim formations, and flange sections extending inwardly from said apron sections, said counter top being formed from a one piece metal sheet forming the facing surfaces for said table section, rim formations, apron sections and flange sections, a fibrous backing section bonded to said metal facing sheet presenting backing support for the table section of said metal facing sheet, fibrous apron backing sections bonded to said metal sheet each providing a backing support for the adjacent apron section and the adjacent rim formation of said metal sheet, the adjacent ends of said apron backing sections being mitre cut to provide spaced substantially parallel end faces presenting an open joint therebetween, said apron sections of the metal sheet having a lip portion at the adjacent ends thereof extending inwardly and in hugging contact with the adjacent mitred end of the adjacent apron backing section, the adjacent metal lip portions being in face-to-face contact, and a stiffening frame formed from stiffening strips of fibrous material seating within the pocket formed by the adja-

cent apron sections and associated flange sections providing a counter top presenting finished metal facing surfaces supported and reinforced by said backing sections and stiffening frame.

7. An improved counter top construction having a table top section, raised rim formations extending along adjacent peripheral edges of said table section, and apron sections depending from said rim formations, said counter top being formed from a one piece metal sheet forming the 10 facing surfaces for said table section, rim formations and apron sections, a fibrous backing section bonded to said metal facing sheet providing a backing support for the table section of said metal facing sheet, and fibrous apron backing sections bonded to said metal sheet each providing a backing support for the adjacent apron section and the adjacent rim formation of said metal sheet, the adjacent ends of said apron backing sections being mitre cut to provide spaced substantially parallel end faces presenting an open joint therebetween, each of the apron sections of the metal sheet having a lip portion at the end thereof extending inwardly and in overlying contact with the adjacent mitered end of the adjacent apron backing section, the adjacent metal lip portions being in face-to-face contact, and a seam of bonding metal covering the exterior joint between said inturned lip portions bonding said lip portions into integral union.

8. An improved counter top construction having a table top section, raised rim formations extending along the peripheral edges of said table section, apron sections depending from said rim formations, and flange sections extending inwardly from said apron sections, said counter top being formed from a one piece metal sheet shaped to form the facing surfaces of said table section, rim formations, apron sections and flange sections, a fibrous backing section bonded to said metal facing sheet providing backing support for the table top section of said metal sheet, fibrous apron backing sections bonded to said metal sheet each presenting a backing support for the adjacent apron section and the adjacent rim formation of said metal sheet, the adjacent ends of said apron backing sections being mitre cut to provide spaced substantially parallel end faces presenting an open joint therebetween, each of said apron sections of the metal sheet having a lip portion at each end thereof extending inwardly and in overlying contact with the adjacent mitered end of the adjacent apron backing section, the adjacent metal lip portions being in face-to-face contact, and a seam of bonding metal covering the exterior joints between said inturned lip portions bonding said lip portions into integral union.

9. An improved counter top construction having a table top section, raised rim formations extending along the peripheral edges of said table section, apron sections depending from said rim formations, and flange sections extending inwardly from said apron sections, said counter top being formed from a one piece metal sheet forming the facing surfaces for said table top section, rim formations, apron sections and flange sections, fibrous backing sections bonded to said metal facing sheet to provide backing support for the table section; apron sections, rim formations, and flange sections of said metal facing sheet, the adjacent ends of said fibrous backing sections being mitre cut to provide spaced substantially parallel end faces presenting an open joint therebetween, said apron sections of the metal sheet having a lip portion at the adjacent ends thereof extending inwardly and in hugging contact with the adjacent mitered end of the adjacent apron backing section, the metal lip portions being in face-to-face contact, and a seam of bonding metal covering the exterior joint between said inturned lip portions bonding said lip portions into integral union, a stiffening frame formed from stiffening strips of fibrous material seating within the pocket formed by the adjacent apron sections and associated flange sections, the space defined within said stiffening frame being filled with fibrous filler providing a counter top presenting finished metal facing surfaces supported and reinforced by said backing sections, stiffening frame and fibrous filler.
